UNITED STATES PATENT OFFICE

118,129

DESIGN FOR A BROOCH OR SIMILAR ARTICLE

Charles E. Pauzat, New York, N. Y., assignor to Cohn & Rosenberger, Inc., New York, N. Y., a corporation of New York

Application October 28, 1939, Serial No. 87,912

Term of patent 7 years

To all whom it may concern:

Be it known that I, Charles E. Pauzat, a citizen of the Republic of France, residing at New York, in the county of New York and State of New York, have invented a new, original, and ornamental Design for a Brooch or Similar Article, of which the following is a specification, reference being had to the accompanying drawing, forming part thereof.

In the drawing:

Fig. 1 is a plan view of a brooch or similar article showing my new design.

Fig. 2 is an edge view thereof.

I claim:

The ornamental design for a brooch or similar article, as shown.

CHARLES E. PAUZAT.
